UNITED STATES PATENT OFFICE.

HERMANN ROMÜNDER, OF MILWAUKEE, WISCONSIN.

METAL SKELETON FRAME CONSTRUCTION FOR PASSENGER-CARS.

SPECIFICATION forming part of Letters Patent No. 782,059, dated February 7, 1905.

Application filed April 26, 1904. Serial No. 204,964.

To all whom it may concern:

Be it known that I, HERMANN ROMÜNDER, a citizen of the United States, and a resident of Milwaukee, county of Milwaukee, and State of 5 Wisconsin, have invented certain new and useful Improvements in Metal Skeleton Frame Constructions for Passenger-Cars, of which the following is a specification.

My invention aims to provide a car that is 10 much stronger and more substantially built, more rigid, and of greater resisting power, especially to lateral tension and strains, than those now generally manufactured and used and that will afford greatest strength and wear- 15 ing power, combined with simplicity of construction, without materially increasing the weight of the car or its manufacturing cost.

I intend my improved metal skeleton frame construction to be adapted more particularly 20 for passenger-cars of the convertible and semi-convertible type for local traction and inter-urban electric service; but I do not, of course, limit myself to such, as the same improved construction may also be applied for passenger cars and coaches and similar vehicles, whether open, convertible, or closed and whether operated by electricity, cable, steam, or other power.

My present invention is an improvement on 30 a former application, filed August 20, 1903, Serial No. 170,130, in which I show a metal skeleton construction for passenger-cars composed of a metal bottom frame formed of metal side and cross sills, a metal side or body 35 frame formed of a number of metal side posts or ribs, the lower portion of which is substantially straight and vertical and the upper portion curved on the arc of a circle, and lateral metal stiffening bars or braces riveted to said 40 side posts at their upper portion and a metal roof-frame formed of a number of curved metal rafters and metal supporting-brackets, the said brackets being riveted to the metal side posts and connected to and supporting 45 the rafters at their outer ends.

In my present invention I employ in place of the system of single lateral braces or diagonals between the side posts at their lower portion and the metal length-bars connecting 50 the several side posts at their upper portions,

as described and claimed in my former application sets of metal braces or counter-diagonals as tension members and substantially longitudinal metal bars as top, center, and bottom chords, forming substantially a metal 55 truss-frame between two or more or all the side posts of a car-body in their lower straight portion, and connect the outer ends of the curved rafters and the supporting-brackets with the metal side posts by means of substantially vertical metal link-pieces, and also connect these link-pieces by means of metal bars extending substantially the entire length of the car-body about at the height of the letter-board, and also provide a number of metal 60 struts connecting the said link-pieces and the horizontal metal bars. I also provide a number of metal braces or counter-diagonals and chords between the upper portions of the metal side posts of the end sections at both ends of 65 the car-body substantially from the level of the window-sill to the level of the rafter-brackets and letter-board for the purpose of stiffening the side or body frame laterally, as illustrated in the section shown to the left of 70 Figure 1. Additional auxiliary metal rafters may also be provided between the principal rafters C and secured at their outer ends to the horizontal metal bars connecting the link-pieces.

My present invention therefore consists, mainly, in the novel features and devices above outlined, as hereinafter fully set forth, and defined in the claims.

One form of my invention is shown in the 85 accompanying drawings, wherein like characters of reference indicate like parts throughout the several views.

Fig. 1 is a side view of the metal skeleton frame construction of part of a passenger-car body embodying my invention, showing 90 two side sections and one end section. Fig. 2 is a transverse vertical section of one-half of the car-body substantially on line 11 of Fig. 1. Fig. 3 is a detail showing in section, on 95 an enlarged scale, a portion of the upper part of the metal frame of the car-body.

A A are the metal side posts, suitably connected at the bottom to the metal side sills B at certain distances apart.

C C are the curved metal rafters, suitably secured at their outer ends to metal supporting-brackets D and link-pieces E E, the said brackets D and link-pieces E being riveted or 5 otherwise suitably fastened to the metal side posts A A.

F F are metal bars extending substantially the entire length of the car-body about the height of the letter-board and are riveted or 10 otherwise suitably connected to the metal link-pieces E E.

G G are metal struts riveted to the metal link-pieces E E and the metal bars F F.

H H are metal braces or counter-diagonals, 15 and K K are metal bars forming top, center, and bottom chords, the said counter-diagonals H H and chords K K being riveted to the side posts and forming substantially metal truss-frames between the side posts at their lower 20 portion approximately from the level of the side sills to about the level of the window-sills. These metal truss-frames, with their counter-diagonals H H and chords K K, may be arranged between two or more or all the 25 side posts of the car-body at their lower portion and preferably also between the upper portions of the metal side posts of the end sections at both ends of the car approximately from the level of the window-sills to the level 30 of the rafter-brackets D and letter-board for the purpose of laterally stiffening the side or body frame.

L L are additional auxiliary rafters, of metal or other suitable material and construction, 35 that may be provided between the principal rafters C C and suitably connected to one or both of the metal bars F F.

By means of these metal braces, counters, 40 struts, and trusses I reinforce the metal skeleton frame described in my former application and accomplish an absolutely uniform distribution of the lateral tension and strains over the metal bottom, side or body, and roof frame and obviate the possibility of swaying 45 or shifting of the top portion or roof-frame of the car-body on account of lateral thrusts or strains, and as these said metal braces, counters, struts, and trusses may be comparatively light they will not materially increase the 50 weight of the car-body, but greatly add to its strength, rigidity, and wearing power, while maintaining its simplicity of construction and low manufacturing cost.

I disclaim all matter here shown and described which is claimed in my former application.

What I claim is—

1. A metal skeleton frame for passenger-cars, composed of a suitable metal bottom 60 frame, a metal side or body frame and a metal roof-frame, metal link-pieces, connecting the metal rafters and metal side posts of the body and roof frame, metal bars, suitably connected to the said link-pieces and extending substantially the entire length of the car-body,

and metal struts, riveted to the metal link-pieces and longitudinal bars; and a number of counter diagonal braces and a number of metal chords, riveted to the metal side posts and forming substantially truss-frames between 70 two or more or all the side posts at their lower portions and between the upper portions of the metal side posts of the end sections at both ends of the car-body, substantially as shown and described.

2. A metal skeleton frame for passenger-cars, composed of a suitable metal bottom frame, a metal side or body frame and a metal roof-frame, and a number of metal braces or counter-diagonals and a number of metal bars 80 or chords, riveted to the metal side posts of the end sections at both ends of the car-body, at their upper and lower portions, approximately from the side sills to the level of the rafter-brackets, and to two or more or all the 85 side posts at their lower portions, approximately from the side sills to the level of the window-sills, the said counter-diagonals and chords forming substantially metal truss-frames between said side posts; and metal 90 link-pieces, supporting the metal rafters and connecting the outer ends of said rafters with the metal side posts, longitudinal metal bars, suitably secured to said metal link-pieces and extending substantially the entire length of 95 the car-body, metal struts, riveted to the said link-pieces and longitudinal bars, and additional auxiliary metal rafters, provided between the principal rafters and suitably secured to the said longitudinal bars, all substantially as shown and described.

3. A metal skeleton frame for passenger-cars, composed of a number of metal side posts and metal rafters, forming a metal body and roof frame, a number of metal chords and 105 metal counter-diagonals, suitably riveted to and forming metal truss-frames between any desired number of side posts of the car-body, and a number of metal link-pieces, suitably connected to the metal rafters and side posts 110 and to metal bars, extending substantially the entire length of the car-body, and to metal struts; the said truss-frames, link-pieces, bars and struts forming a metal skeleton framework, reinforcing the said metal roof and 115 body frame, substantially as shown and described.

4. In a metal skeleton frame for passenger-cars metal truss-frames provided between a number of metal side posts at their lower portions, approximately from the side sills to the level of the window-sills, and between the side posts of the end sections at both ends of the car-body, at their upper portions, approximately from the level of the window-sill to the level of the rafter-brackets and letter-board, the said metal truss-frames being formed by counter diagonal metal braces or tension members and metal bars or chords, suitably riveted to the metal side posts, for the purpose of re- 130

inforcing the metal side or body frame of the car, substantially as shown and described.

5. In a metal skeleton frame for passenger-cars metal link-pieces, suitably connected to the metal side posts and rafters of the car-body, and longitudinal metal bars, suitably connected to said link-pieces and extending substantially the entire length of the car-body, and metal struts, riveted to the said longitudinal metal bars and the said metal link-pieces, and auxiliary rafters, suitably secured to the said metal bars; the said longitudinal bars, link-pieces, struts and auxiliary rafters forming a metal skeleton framework reinforcing the metal roof and body frame of the car, substantially as shown and described.

6. In a metal skeleton frame for passenger-cars metal link-pieces, metal struts and metal bars suitably connected to each other and forming together with auxiliary metal rafters a metal skeleton framework, suitably secured to and reinforcing the metal side posts and metal rafters, forming the side or body and the roof-frame of the car; the said metal bars

extending substantially the entire length of 25 the car-body at a suitable height, and the auxiliary rafters being suitably connected to the said metal bars, substantially as shown and described.

7. The above-described metal frame construction for passenger-cars composed of metal trusses provided between the metal side posts of the car-body and suitably connected thereto; metal link-pieces connecting the outer ends of the metal rafters and the metal side posts; 30 metal bars extending substantially the entire length of the car-body at a suitable height and riveted to the said metal link-pieces; and metal struts suitably secured to the said metal link-pieces and the said metal bars, substantially 35 40 as shown and described.

In testimony whereof I affix my signature in presence of two witnesses.

HERMANN ROMÜNDER.
